UNITED STATES PATENT OFFICE

JOSEPH KONIGSBERG, OF NEW YORK, N. Y.

STEPLADDER

Application filed October 15, 1927. Serial No. 226,319.

This invention relates to step-ladders used by artisans and others upon substantially level surfaces to reach otherwise inaccessible heights.

5 Commercial step-ladders ordinarily consist of a pair of risers connected by fixed treads and pivotally joined at their tops to rear legs or struts, also rigidly connected together from side to side, the over-all width 10 of the risers and struts being essentially the same.

As such ladders are commonly quite narrow at their bases, they are easily tipped over sidewise by persons in reaching laterally outward, 15 beyond the center of gravity, causing falls and consequent injury.

It is therefore the principal object of the present invention to provide a step-ladder in which the struts are pivotally connected to 20 the ladder at their upper ends, permitting angular separation or spread at their bottoms to any requisite degree, and means combined therewith for rigidly maintaining them in such adjustment.

25 Another important object is to provide means whereby the struts may be extended at various angles rearwardly relative to the risers and securely held in adjustment by a single element.

30 A further feature is in the provision of a step-ladder having essentially three points of support and hence substantially free from danger in tipping sidewise.

Other advantageous features include a 35 collapsible platform suspended in a novel manner in the upper portion of the ladder, and having means to prevent displacement when collapsed and the ladder folded.

40 These and other objects are attained by the novel construction, combination and arrangement of parts hereinafter described and shown in the accompanying drawing, constituting a material part of this disclosure and 45 in which:—

Figure 1 is a front elevational view of a step ladder made in accordance with the invention, the parts being in a folded position.

50 Figure 2 is a front elevational view of the same, showing the struts as fully extended in

full lines and as partially extended in broken lines.

Figure 3 is a side elevational view of the ladder as arranged with reference to a vertical wall, with one of the struts broken away to 55 show the strut clamping means.

Figure 4 is another side elevational view of the device as when fully extended.

Figure 5 is a fragmentary sectional view 60 of the clamping means, the section being taken substantially on line 5—5 of Figure 3.

As indicated in the drawing, the front portion of the ladder is of conventional design consisting of a pair of risers 10 connected by a plurality of rungs 11, 11^a, 11^b, 11^c, etc. and having between them a series of treads 12, 12^a, 12^b, 12^c, etc. disposed immediately above the rungs.

As the rungs pass through the risers, in 70 which they are firmly secured, and the treads are arranged to abut the inner sides of the risers, it will be seen that an exceptionally firm structure is provided.

The tops of the risers are cut at an angle and have engaged over them a top plate 13 arranged preferably to overhang the sides and also extend slightly to the rear. Immediately below the top plate is a cleat 14 arranged transversely and on each of the rear edges 75 of the risers are secured strap brackets 15 presenting eyes 16 midway in their lengths in which are journalled pintles 17 extending oppositely outward from a hollow metallic frame or casing 17; obviously other analogous means may be used for pivotally connecting 80 the casing to the brackets.

A pair of struts 18 are pivotally engaged 85 independently to the casing 17 by pivot bolts 19, and rigidly secured to the inner side of the casing 17 is a narrow sheet metal strip 20 extending vertically downward past the center of the ladder and having in its lower portion a slot 21.

Slidable, but non-rotatable, in the slot is a 90 clevis bolt 22 having a reduced screw-threaded portion 23 passing through the openings in the adjacent inner ends of a pair of links 24, pivoted at their outer ends to the struts 18, the bolt being provided with a clamp nut 25 95 having a conveniently operable lever handle. 100

Pivoted on a screw 26, passing through the head of the clevis bolt 22 is a rod 27 having at its outer end a hook 28, provided with an elongated point adapted to engage selectively in any of the openings 29 formed near the rear edge and at the center of the several steps 12^a, 12^b or 12^c.

From the foregoing it will be seen that when the struts 18 are spread to their utmost extent, the links 24 will assume a substantially horizontal position, the bolt 22, at that time being in the lowermost portion of the slot 21, and it will be apparent that upon moving the struts 18 inwardly, as shown in the broken line position in Figure 2, the links 24 will assume an angular position and the bolt 22 be raised, so that when the struts are in close proximity, it will be nearly or quite at the top of the slot, and due to the clamping nut 25, the struts are held rigidly in any adjusted position in which they may be placed, as shown in Figure 2.

It is sometimes desirable to erect a ladder closely adjacent an upright wall, in which case by placing the hook 28 in the opening 29 in the tread 12^a, the struts will be held substantially vertical, while if the hook be placed in the opening in the tread 12^c the struts will be extended at an extreme angle from the risers as shown in Figure 4.

As the hook rod 27 securely but pivotally engages with the head of the clevis bolt 22, it will be seen that the struts are always held in rigid relation to the risers, except when it is desired to collapse the ladder, at which time the bolt will be disposed in the uppermost part of the slot 21, the hook disengaged from the treads and permitted to hang pendant.

In order to render it impossible to spread the struts and risers beyond a safe limit, in case it is forgotten to engage the hook, a safety chain 35 is attached at its ends respectively to the bolt 22 and step 12^b or its corresponding rung 11^b as seen in Figures 3 and 4.

A pair of pivots 30', set in upper ends of the risers, carry a pair of normally pendant links 30 having pivotally attached at their lower ends the sides 31 of a platform or seat 32 adapted to swing between the risers 10, as shown best in Figures 3 and 4, in which views will also be seen that the platform sides 31 are notched so as to engage over the rung 11^d, thus preventing swinging of the platform 55 and providing a firm support.

When it is not desired to make use of the platform it is folded to hang pendant adjacent the links 30, said links having recesses 33 in their lower ends adapted to engage the rung 11^d when the ladder is collapsed and at the same time lugs 34 on the lower edges of the side elements 31 engage the front side edges of the links, thereby maintaining the platform in an inoperative position between the risers and struts.

From the foregoing it will be seen that the risers, regarded as a unit, together with the struts when spread at their bases and held at an angle outwardly, present a substantially three point surface contact, tending to unusual safety and firmness in use. 70

As all the adjustments are maintained by a single, easily actuated and efficient clamping means, together with a single central hook rod, the structure possesses an exceptional degree of rigidity when in use, and permits compact folding for storage or transportation, rendering the device desirable because of its advantageous features. 75

The foregoing disclosure is to be regarded as descriptive and illustrative only, and not as restrictive or limitative of the invention, of which obviously embodiments may be constructed including many modifications without departing from the general scope herein indicated and denoted in the appended claims. 80

Having thus described my invention, what I claim as new and desire to secure by Letters Patent, is:— 90

1. A step ladder having fixed risers and a pair of struts, said struts having connections permitting limited lateral angular movement therebetween and a swinging movement relative to said risers, a single control means for the swinging movement whereby variable angular positions may be obtained, and a single clamping means for the angular movement between said struts the angle of which may be widely variant, said clamping means being fixed centrally between the struts. 95

2. A step ladder having fixed risers, a casing pivoted on a transverse axis at the upper portion of said risers, a pair of struts pivoted in spaced relation in said casing to swing towards and from one another, means to equalize the angular inclination of said struts, and means for clamping the struts in any angular adjustment. 105

3. A step ladder having fixed risers, a casing pivoted on a transverse axis at the upper portion of said risers, a pair of struts pivoted in spaced relation in said casing to swing towards and from one another, a slotted downwardly extending plate fixed on said casing to reach below the center of length of said struts, a pivot bolt slideable in the plate slot, links pivotally attached to said struts connecting with said bolt, and a manually operable nut on said bolt to clamp the links to said plate. 110

4. A step ladder having fixed risers, a casing pivoted on a transverse axis at the upper portion of said risers, a pair of struts pivoted in spaced relation in said casing to swing towards and from one another, a slotted downwardly extending plate fixed on said casing, a pivot bolt slideable in the plate slot, links pivotally attached to said struts con- 125

necting with said bolt, a lever actuated nut on said bolt to clamp the links and plate when said struts are in adjustment, and means pivoted in the head of said bolt to selectively engage the steps of the ladder whereby the 5 risers and struts are held in adjustment.

5. A step ladder comprising a pair of risers having treads therebetween, brackets on the upper rear portions of said risers, a casing having pintles rotatable in said brackets, a 10 pair of struts pivoted independently in said casing to swing towards and from each other, a down reaching slotted plate bar fixed on said casing, a bolt slidable in the slot of said bar, links pivoted to said struts and engaged by said bolt at their inner ends, a manually operable nut on said bolt to clamp said links when said struts are in an 15 adjusted position, and means carried by said bolt, cooperative with said treads to retain said risers and struts in angular adjustment.

6. A step ladder having parallel risers and struts pivoted thereto to move angularly with respect to each other and to swing as a 20 unit relatively to the risers, a rod pivoted to said struts said rod having a right angularly bent portion to engage selectively in opening in certain of the risers whereby they may be held in different adjusted positions, and a 25 flexible connection between said struts and risers limiting the angle therebetween, said struts being foldable against the ladder treads when the ladder is collapsed.

7. A step ladder having fixed risers and a 30 pair of struts, said struts being pivoted to present opposed angular inclinations with respect to each other and to move as a unit with respect to said risers, treads fixed between said risers, said treads having perforations in their rear central portion, a single 35 rigid means to control the angular movement between said struts and risers, said means being selectively engageable in the perforations of said treads, and a flexible means to 40 limit the ultimate movement therebetween.

45 8. A step ladder having fixed risers and a pair of struts, said struts having connections permitting limited lateral angular movement therebetween and a swinging movement relative to said risers, a slotted bar extending rigidly from said connections below the center of length of the ladder, and a single 50 control means for the swinging movement said means being adjustable in the slot of said bar.

55 In testimony whereof I affix my signature.
JOSEPH KONIGSBERG.
